UNITED STATES PATENT OFFICE

MAHALA WARREN, OF WETUMKA, OKLAHOMA

DESIGN FOR A VALENTINE ENVELOPE

Application filed April 22, 1930. Serial No. 35,341. Term of patent 7 years.

To all whom it may concern:

Be it known that I, MRS. MAHALA WARREN, a citizen of the United States, residing at Wetumka, Oakmulgee St. 114, in the county of Hughes and State of Oklahoma, have invented a new, original, and ornamental Design for Valentine Envelopes.

Figure 1 is a plan view of a valentine envelope in open position, showing my new design. Figure 2 is a face view of the valentine envelope shown in Figure 1, in closed position.

I claim:

The ornamental design for a valentine envelope, as shown.

MRS. MAHALA WARREN.
